FLOUR SIFTER OR THE LIKE

James J. Swett, Barrington, and Henry J. Marien, Warwick, R.I., assignors to Rexall Drug and Chemical Company, Los Angeles, Calif., a corporation of Delaware

Filed June 30, 1964, Ser. No. 80,641

Term of patent 14 years

(Cl. D44—29)

FIG. 1 is a perspective view of a flour sifter or the like, in inverted position, showing our new design;

FIG. 2 is a perspective view thereof in upright position;

FIG. 3 is a bottom plan view;

FIG. 4 is a top plan view; and

FIG. 5 is an elevational view.

The essential features of our design are shown in full lines on the drawing.

We claim:

The ornamental design for a flour sifter or the like, as shown and described.
